UNITED STATES PATENT OFFICE.

JOHN RICHARD DEARDEN, OF SAXONVILLE, MASSACHUSETTS.

MACHINERY FOR DRYING SKEINS OF YARN.

SPECIFICATION forming part of Letters Patent No. 328,470, dated October 20, 1885.

Application filed September 6, 1884. Serial No. 142,343. (No model.)

To all whom it may concern:

Be it known that I, JOHN RICHARD DEARDEN, of Saxonville, in the county of Middlesex, of the Commonwealth of Massachusetts, have invented a new and useful Improvement 5 in Machinery for Drying Skeins of Yarn; and I do hereby declare the same to be described in the following specification, and represented in the accompanying drawings, of which—

10 Figure 1 is a top view, Fig. 2 a side elevation, Fig. 3 a horizontal section, and Fig. 4 a vertical section of a machine embodying my invention, the nature of which is defined in the claims hereinafter presented. Fig. 5 is a 15 top view, and Fig. 6 a longitudinal section, of a number of skeins as connected by the binding-warps or endless tapes or cords, to be described. Figs. 7 and 8 are hereinafter referred to and explained.

20 By the above-mentioned machine the skeins of yarn are, like the weft-threads of cloth when arranged parallel to each other, connected by a warp, there being generally employed for such warp two sets of endless 25 cords or tapes having two or three cords or tapes to each set. I term these connecting cords or threads "binding-warps," thus serving to connect the skeins so as to form a belt of them. This belt is led through and out of 30 a drying apparatus, in going through which the skeins composing the belt are dried. From this drying apparatus the belt passes to or by and is subjected to the action of mechanism by which the binding-warps are drawn 35 away from the skeins, so as to enable the latter to fall apart or separate from each other.

In the said drawings, A denotes the frame of the machine, having within it a table or platform, B, from which there is extended 40 downward, as shown in Fig. 2, a curved inclined chute, C. In the top of the said table is a series of parallel slots or openings, a, extending transversely across the said top. In each of these slots or openings a is a rod or 45 warp-carrier, b, the slot or opening serving not only as a guide to the rod in its vertical movements, but as a recess or passage for a set of the binding-warps to go through. Each rod b, at its lower part, is pivoted to a vi- 50 bratory arm, c, there being two sets of such arms, one of which projects from one rock-shaft, d, and the other from another rock-

shaft, e, arranged as represented in the drawings.

Each rod b has a hole, f, through it, near its 55 upper end, to receive a binding-warp, which goes through it. These warps are endless tapes or cords, they being shown at g,g. The rods operate, like the harnesses of a loom, to raise some of the warps and depress others, in 60 order for a shuttle carrying a weft-thread to be thrown between the two sets of warps; but instead of a shuttle I have mechanism for drawing the skeins successively through the "shed" of the warps—that is to say, I use a 65 rod arranged horizontally and bent upward near one end at a right angle. This rod (shown at h) I term the "skein-introducer." It is first run through the shed or opening between the crossed warps, after which a skein 70 is hitched on the upturned part of the rod. The rod next is drawn backward, so as to pull the skein into the shed to the necessary extent. The rod next drops a short distance, sufficiently for its disengagement with the 75 skein, after which the warp-carriers b are moved—some upward and the rest downward—so as to cross their warps upon the skein. As soon as the skein may be laid between the crossed warps and disconnected 80 from the introducer, a beater is driven forward against the skein to force it into the shed of the warps, as the lay of a loom acts to beat the filling into the warp. This beater will be hereinafter described. After a skein 85 may have been so bound the warps are moved forward a sufficient distance for the next skein to be introduced between them, and close against and parallel to the other, by means of the skein-introducer. For this purpose the 90 warps may have either an intermittent or a slow continuous motion.

As hereinbefore stated, each warp g is an 95 endless band, tape, or cord. It passes down the chute C, and thence about a series of rollers, D, arranged in a drying chamber or box, E. These rollers have sprocket-gears i on their shafts to engage with an endless chain, k, carried around a series of supporting and guide gears, l. There is fixed on the shaft of 100 one of the warp-guide rollers a beveled gear, m, which engages with a bevel-pinion, n, fixed on an inclined shaft, o, supported in suitable boxes, p. On the lower end of the shaft o is

fastened another bevel-pinion, q , that engages with another such pinion, r , fixed on a horizontal shaft, s . The pinion r engages with another bevel-pinion, t , carried by the driving-shaft u of the machine. On this shaft is a fast pulley, v , and a loose pulley, w , the shaft being properly supported in bearings x , applied to standards y .

The beater is represented at F. It consists of a series of rods or arms, z , and a horizontal rock-shaft, a' , from which the said arms project upward through slots in the table, and between the ranges of endless binding-warps. A connecting-rod, b' , is pivoted to one of the arms z and to a short lever, c' , from which a stud, d' , extends into the groove of a cam, e' , fixed on the shaft s . When the shaft s is in revolution, a reciprocating vibratory movement will be imparted to the beater F.

To operate the skein-introducer h —that is, to move it lengthwise on its ways h^4 first in one and next in the opposite direction—I attach to the block h^1 , to which the introducer at its rear end or part is pivoted, the two ends 25 of a band, f' , going, as shown in Fig. 7, around a large pulley, g' , and a smaller one, h' , and partially around two small rolls, g^2 h^2 , supported by the frame, the said figure being a view to exhibit the arrangement of the introducer 30 and its operative band and pulleys. The pulley g' is fixed on the shaft i' , provided with a spur-gear, k' , which engages with a geared sector, l' , carried by a lever, m' , from whose shorter arm a stud, n' , extends into a grooved cam, o' , fixed on the driving-shaft u .

When the cam o' is in revolution, a reciprocating vibratory motion will be imparted to the lever m' , whereby the toothed sector will be made to turn the gear k' first in one and 40 next in the opposite way, whereby the skein-introducer will be drawn in between and next out of the binding-warps. Each binding-warp goes partly about one or more pulleys or sheaves, p' , drawn downward by a weight, q' , to each, such pulley and weight being to 45 keep the warp at a proper tension.

The belt of skeins after emerging from the drying apparatus passes down an inclined plane, H, and underneath a presser-bar, I, arranged above the plane and resting on the band, so as to prevent it from being pulled 50 sidewise off the inclined plane by the binding-warps while they are drawn laterally out of the belt.

On each side of the path of the belt, down 55 the inclined plane, there is arranged a series of guide-pulleys, r' , against the peripheries of which the several next adjacent binding-warps are run, the said pulleys being arranged so as to cause the warps to be drawn 60 laterally out from between the skeins, from whence they each pass partly about a pulley, s' . Thence they pass to and partly around guide-pulleys u' ; thence around other guide-pulleys, 65 t' , and the weighted sheaves; thence to and over a pulley, v' , pivoted to the table, as rep-

resented. Each set of warps between which the presser is arranged has a separate mechanism, as described, for extracting it from the skeins.

The drying chamber or box is to have within or applied to it some suitable means of heating the air passing through it—such as shown, being a series of pipes, t^2 , properly arranged for steam to pass through them and 75 heat them.

From the above, it will be seen that the skeins in a wet state, as they usually are after being washed, are to be successively introduced into the shed of the warps, and that 80 such warps are to be woven upon the skeins in a manner very like that in which warps are woven on weft-threads in the weaving of cloth; also, that the belt of skeins is moved forward through the drying apparatus, and 85 after exit therefrom the warps are drawn laterally out of the belt, and the skeins are forced down and off the inclined plane H.

The skein-introducer has mechanism for depressing it out of engagement with the 90 skein after the latter may have been drawn into the shed of the warps. The introducer slides through a block, w' , which is movable in guides $x' x'$, and is pivoted to a rod, y' , that is pivoted to a lever, z' , which at the proper 95 times is moved by a cam, s' , to throw it upward and to depress it. Fig. 6 is a view of this mechanism, such view exhibiting the cam as fixed on the driving-shaft.

I claim—

1. The combination, substantially as described, for interweaving a series of skeins and a series of binding-warps, such combination consisting of the slotted table B, and the warp-carrying rods b , the skein-introducer h , 105 and the beater F, and their operative mechanisms, essentially as described and represented.

2. The combination of the series of endless warps provided with mechanism, substantially 110 as described, for supporting them and maintaining them at proper tension with the table B, and the warp-carrying rods b , the skein-introducer h , and the beater F, provided with mechanisms for operating them, essentially as 115 set forth.

3. The combination of the series of endless warps provided with mechanism, substantially 120 as described, for supporting them and maintaining them at proper tension with the table B, and the warp-carrying rods b , the skein-introducer h , and the beater F, having mechanisms for operating them, as explained, and also with the drying box or chamber, and the inclined plane H, and presser-bar I, and rollers r' , substantially as described, for extracting 125 the warps, all being essentially and for the purpose or purposes, as specified.

JOHN RICHARD DEARDEN.
